UNITED STATES PATENT OFFICE.

ABRAHAM L. YATES, OF NIAGARA FALLS, NEW YORK.

INDEXED BOOK.

SPECIFICATION forming part of Letters Patent No. 639,487, dated December 19, 1899.

Application filed April 14, 1899. Serial No. 713,028. (No model.)

To all whom it may concern:

Be it known that I, ABRAHAM L. YATES, a citizen of the United States, residing at Niagara Falls, in the county of Niagara and State 5 of New York, have invented certain new and useful Improvements in Indexed Books; and I do hereby declare the following to be a full, clear, and exact description of the invention, such as will enable others skilled in the art to 10 which it appertains to make and use the same.

This invention relates to indexed books; and it consists in the novel construction and combination of the parts hereinafter fully described and claimed.

15 In the drawings, Figure 1 is a perspective view of the book with a portion of its cover removed and some of its pages turned up. Fig. 2 is a plan view of one of the detachable pages of the book.

20 A is the index-page of the book, which is preferably its first page.

B are the permanent blank or copy pages of the book. The first blank page B under the index-page A is provided with an extension or tab b at its right-hand upper corner, and the remaining pages B are provided with similar extensions or tabs b, arranged vertically under the first extension or tab and in a stepped progression. Each extension or 25 tab is provided with a separate indication or mark—such as a numeral, letter, blank space, or symbol—to distinguish its page from the other similar pages, and the index-page A is provided at b' with similar indications or 30 marks—such as numerals, letters, blank spaces, or symbols—to correspond with those on the tabs or extensions and preferably arranged horizontally in line with them.

The index-page A is ruled with horizontal 40 and vertical lines according to the purpose for which the book is to be used. As shown, the book is arranged to be used as a bill and account book; but it may be used for other purposes, such as a letter-book or a doctor's 45 prescription-book.

C are pages interleaved between the blank pages B and provided with a row of perforations c, so that the greater portion of each page C can easily be detached and removed

from the book. The pages of the book are all 50 bound up together and are provided with a cover D. The pages B and C are preferably arranged in pairs; but, if desired, two or more similar pages C can be arranged next to each page B to which they may pertain, instead 55 of a single page C. The pages C have no tabs or extensions and are ruled off and printed like ordinary bill-heads or letter-heads or otherwise according to the purpose of the book.

E is a removable sheet of carbon-paper, 60 which is placed loosely between any two pages B and C when the book is used, so that a copy of the matter written upon any permanent page C is formed upon the detachable page B to which it pertains. 65

When the book is used as a bill and account book, the name of each customer to whom goods are sold is entered on the index-page and the amount of his bill in the column marked "Dr." If he pays his bill in part, 70 the part paid is entered in the column marked "Cr." and the balance in the column marked "Bal." The bill itself is written on the page C, and is copied by the carbon-paper onto the page B, which is marked to correspond with 75 the mark on the index-page, and the entry on the index-page is in line with the mark on the page B pertaining to it. The bill on the page C is detached and given to the customer, and the copy of the bill on page B remains 80 permanently in the book with the index.

What I claim is—

1. In an indexed book, the combination, with a series of permanent pages provided with distinguishing marks upon extensions or 85 tabs arranged in a stepped progression, of detachable pages arranged between the said permanent pages, and a single superposed index-page bound up with all the said pages and marked to correspond with the said permanent pages, the said detachable pages and index-page being arranged so as not to cover the said extension or tabs, substantially as set forth.

2. In an indexed book, the combination, 95 with a series of permanent pages provided with distinguishing marks upon extensions or tabs arranged in a stepped progression, of a

series of detachable pages arranged in alternation with the said permanent pages, and a single superposed index-page bound up with all the said pages and marked to correspond 5 with the said permanent pages at a series of points in line with the marks on the said extensions or tabs, substantially as set forth.

In testimony whereof I affix my signature in presence of two witnesses.

ABRAHAM L. YATES.
